US00D847905S

(12) **United States Design Patent** (10) **Patent No.:** **US D847,905 S**
(45) **Date of Patent:** ** *May 7, 2019

(54) **GAME TOWER**

(71) Applicant: **AGS LLC**, Las Vegas, NV (US)

(72) Inventors: **Rachel Calhoun Lewis**, Atlanta, GA (US); **Ian Robert Scott**, Duluth, GA (US); **Karl Frederick Zedell, Jr.**, Alpharetta, GA (US)

(73) Assignee: **AGS LLC**, Las Vegas, NV (US)

(*) Notice: This patent is subject to a terminal disclaimer.

(**) Term: **15 Years**

(21) Appl. No.: **29/631,060**

(22) Filed: **Dec. 27, 2017**

Related U.S. Application Data

(62) Division of application No. 29/540,396, filed on Sep. 24, 2015, now Pat. No. Des. 813,954.

Primary Examiner — Ryan Harvey

(74) *Attorney, Agent, or Firm* — Weide & Miller, Ltd.

(57) **CLAIM**

The ornamental design for a game tower, as shown and described.

DESCRIPTION

FIG. 1 is a front perspective view from above of an embodiment of the claimed design;

FIG. 2 is a front elevation view of the claimed design of FIG. 1;

FIG. 3 is a rear elevation view of the claimed design of FIG. 1;

FIG. 4 is a first side view of the claimed design of FIG. 1;

FIG. 5 is a second side view of the claimed design of FIG. 1;

FIG. 6 is a top plan view of the claimed design of FIG. 1;

FIG. 7 is a bottom plan view of the claimed design of FIG. 1;

FIG. 8 is a front perspective view from above of another embodiment of the claimed design;

FIG. 9 is a front elevation view of the claimed design of FIG. 8;

FIG. 10 is a rear elevation view of the claimed design of FIG. 8;

FIG. 11 is a first side view of the claimed design of FIG. 8;

FIG. 12 is a second side view of the claimed design of FIG. 8;

FIG. 13 is a top plan view of the claimed design of FIG. 8;

and,

FIG. 14 is a bottom plan view of the claimed design of FIG. 8.

The broken line showing of portions of the gaming tower depicts environment and forms no part of the claim.

1 Claim, 12 Drawing Sheets
